United States Patent Office.

B. WEIRICH AND H. H. SHARTLE, OF MIDDLEBURY, INDIANA.

Letters Patent No. 73,854, dated January 28, 1868.

IMPROVEMENT IN TUBE-WELLS.

The Schedule referred to in these Letters Patent and making part of the same.

TO ALL WHOM IT MAY CONCERN:

Be it known that we, B. WEIRICH and H. H. SHARTLE, of Middlebury, in the county of Elkhart, and State of Indiana, have invented a new and useful Improvement in Well-Tubes; and we do hereby declare that the following is a full, clear, and exact description thereof, which will enable others skilled in the art to make and use the same, reference being had to the accompanying drawing, forming a part of this specification.

The present invention consists in a novel attachment of a screen or covering to the perforated end of a well-tube, for protecting such perforations from the entrance of sand while the tube is being driven.

In the accompanying plate of drawings our improvements in well-tubes are illustrated, the figure being a side elevation of a well-tube, provided with a screen, according thereto.

A, in the drawings, represents a well-tube that, around one end, has a thread, *a*, cut in it, in conjunction with a series of holes, *b*, to allow the water to pass into the tube or pipe; B, a point inserted in end of well-tube A; and C, a wire wound around the well-tube between the several threads *a* thereto.

By means of the construction above described, the advantages hereinbefore enumerated are, as is obvious, secured.

When the well-tube is to be used in fine quicksand, a coarse wire is placed around it, filling the screw-thread, and allowing very fine openings between the coils of the wire for the passage of water. In coarse gravel, a fine wire is applied, leaving larger openings for the passage of the water. The screw-thread also serves to keep the wire in place.

We claim as new, and desire to secure by Letters Patent—

The perforated well-tube, provided with a screw-thread, *a*, around it, to receive different-sized coiled wires, whereby the openings between the coils of said wires are regulated, adapting the tube for use in fine sand or coarse gravel, as herein shown and described.

B. WEIRICH,
H. H. SHARTLE.
